UNITED STATES PATENT OFFICE

2,485,000

DOOR HANDLE

Gerald V. Jakeway, Grand Rapids, Mich., assignor
to Keeler Brass Company, Grand Rapids, Mich.,
a corporation of Michigan

Application November 29, 1945, Serial No. 631,615

11 Claims. (Cl. 292—167)

1

This invention relates to improvements in door handles.

The main objects of this invention are:

First, to provide a door handle well adapted for use on automobile doors, refrigerator doors, and the like, in which the latch or bolt is released by an outward pull on the handle.

Second, to provide a door handle having these advantages which is attractive and finished in appearance and may be readily adapted to harmonize with the ornamental design or characteristics of the door or structure to which the handle is applied.

Third, to provide a door handle which is free from rattle and may be readily applied.

Further objects relating to details and economies of the invention will appear in the description to follow. The invention is defined and pointed out in the claims.

A preferred embodiment of the invention is illustrated in the accompanying drawing, in which:

Fig. 1 is a fragmentary view, partially in section of a structure embodying my invention, certain parts being shown conventionally.

Fig. 2 is a somewhat enlarged fragmentary view on line corresponding to broken line 2—2 of Fig. 1, illustrating certain details of my invention.

Fig. 3 is an enlarged fragmentary view sectioned on line 3—3 of Fig. 1.

Fig. 4 is an enlarged transverse section through the handle on line 4—4 of Fig. 1.

In the embodiment of my invention illustrated, 1 represents a door and 2 a frame or casing into which the door closes. The door comprises an outer panel 3 and is provided with a chamber 4. The supporting or reinforcing plate 5 is mounted on the inner side of the panel to extend across the chamber 4.

The panel and the reinforcing plate are apertured at 59 and 6 to receive the escutcheon member designated generally by the number 7 and comprising the escutcheon finishing plate 8 and the stirrup-like support member 9, which is disposed within the chamber. The member 9 has a threaded opening 10 therein receiving the screw 11 extending through the inwardly turned arm 12 on the plate 5. This manner of securing the escutcheon is an adaptation of that disclosed in my Patent No. 2,102,714, issued December 21, 1937. The screw may be manipulated through the opening 13 in the edge 14 of the door. The bolt or latch 15 is slidably supported at 16 to coact with the keeper 17, the inner end of the bolt being pivotally connected at 18 to the bolt-releasing

2

lever 19 which is pivoted at 20 on the hangers or supports 21 extending from the plate 5. The spring 22 urges the bolt to engaging position. The bolt is retracted by means of the trigger 23, 5 which is pivoted at 24 to engage the lever 19. The trigger 23 is mounted between the spaced side members or arms of the stirrup-like support member 9 of the escutcheon 7 and is pivotally connected to such side members or arms by the 10 pivot 24 as shown in Fig. 2.

The spring 25 is coiled about the pivot 24 and is provided with extending arms at each end, the arm 26 engaging the escutcheon stirrup member while the arm 27 engages the trigger, thus 15 biasing the trigger to retracted position.

The handle, designated generally by the number 28 comprises the handle bar 29, having the shell-like grip 30 mounted thereon and secured thereto, the grip having a finishing shell 31, embracing the shell 30 and comprising a back-member 32 which is secured by flanging the edges of the shell over the same as shown in 33.

The inner end of the handle bar is extended through the escutcheon face plate and pivotally 25 connected at 34 to the trigger which is of trough or channel section as is shown in Fig. 2.

The outer end of the handle bar projects from the outer end of the casing and has a laterally turned lug 35 which is engaged within the supporting plate 5, the panel and the supporting plate being provided with registering openings 36 and 37 receiving the outer end of the handle bar. The outer end of the handle bar is engaged by the 30 resilient supporting and cushioning element 38, 35 which is arranged on the inner side of the supporting plate, this supporting and cushioning element being provided with a metal holder 39 in the embodiment illustrated, and being formed of rubber or other suitable or resilient material.

40 This arrangement supports the handle for tilting and swinging movement on its outer end and also permits limited longitudinal movement such as would result from the swinging movement of the inner end of the handle resulting 45 from its being swung about the pivot of the trigger. The supporting and cushioning element 38 prevents rattling and permits this desired movement.

It should also be noted that the handle nest-50 ingly engages the escutcheon so that a practical dust, water and dirt seal is provided. This is a matter of substantial importance.

I have illustrated and described my invention as I have embodied the same in an automobile 55 door handle. It will be understood that the de-

sign would be modified in accordance to the design of the door and associated parts on which the handle is to be mounted.

With the parts thus arranged an outward pull on the handle actuates the bolt releasing trigger, and through it the bolt is retracted. The parts are returned to initial or normal position on the releasing of the handle. A push on the handle to close the door is sustained by the escutcheon and the yieldable support for the outer end of the handle, although if excessive thrust is given to the handle, the outer end of the grip comes in contact with the door.

I have not attempted to illustrate or describe various modifications and adaptations which I contemplate as it is believed that this disclosure will enable those skilled in the art to embody or adapt my invention as may be desired.

Having thus described my invention, what I claim as new and desire to secure by Letters Pat- 20 ent is:

1. The combination with a door having a chamber therein and comprising an outer panel, a supporting plate mounted on the inner side of said panel to extend over said chamber and apertured to receive an escutcheon member and having a laterally disposed arm adjacent said aperture, an escutcheon member comprising a face element connected thereto and disposed within said chamber covering said aperture and a stirrup-element disposed within said chamber, said stirrup-element having a threaded hole engaged by a screw extending through said arm on said supporting plate whereby the escutcheon member is secured in position, a bolt releasing trigger pivotally mounted in said escutcheon stirrup-member, a spring acting to bias the trigger to retracted position, a handle comprising a handle bar and a casing therefor, the handle bar extending from each end of the casing, the inner end of the handle bar extending through the escutcheon plate and being pivotally connected to the trigger, the outer end of the handle bar terminating in a laterally disposed lug, the panel and supporting plate having openings therein through which the outer end of the handle bar is disposed with its lug engaging the inner side of the supporting plate, and a resilient support disposed on the inner side of said supporting plate in supporting cushioning relation to the outer end of the handle bar permitting swinging and limited longitudinal movement thereof.

2. The combination with a door having a chamber therein and comprising an outer panel, a supporting plate mounted on the inner side of said panel to extend over said chamber and apertured to receive an escutcheon member, an escutcheon member comprising a face element connected thereto and disposed within said chamber covering said aperture and a stirrup-element disposed within said chamber, said stirrup-element having a threaded hole engaged by a screw retainingly connected to said supporting plate whereby the escutcheon member is secured in position, a bolt releasing trigger pivotally mounted in said escutcheon stirrup-member, a spring acting to bias the trigger to retracted position, a handle comprising a handle bar and a casing therefor, the handle bar extending from each end of the casing, the inner end of the handle bar extending through the escutcheon plate and being pivotally connected to the trigger, the outer end of the handle bar terminating in a laterally disposed lug, the panel and supporting plate having open-

ings therein through which the outer end of the handle bar is disposed with its lug engaging the inner side of the supporting plate, and a resilient support disposed on the inner side of said supporting plate in supporting cushioning relation to the outer end of the handle bar permitting swinging and limited longitudinal movement thereof.

3. The combination with a door having a chamber therein and comprising an outer panel, a supporting plate mounted on the inner side of said panel to extend over said chamber and apertured to receive an escutcheon member and having a laterally disposed arm, a bolt retracting lever pivotally mounted on said supporting plate, an escutcheon member comprising a face element connected thereto and disposed within said chamber covering said aperture and a stirrup-element disposed within said chamber, said stirrup-element having a threaded hole engaged by a screw extending through said arm in said supporting plate whereby the escutcheon member is secured in position, a bolt releasing trigger pivotally mounted in said escutcheon stirrup-member in operative relation to said bolt retracting lever, a spring acting to bias the trigger to retracted position mounted on the trigger pivot and having projecting arms, one of which engages the stirrup and the other the trigger, a handle comprising a handle bar and a casing therefor, the handle bar extending from each end of the casing, the inner end of the handle bar extending through the escutcheon plate and being pivotally connected to the trigger, the outer end of the handle bar terminating in a laterally disposed lug, the panel and supporting plate having openings therein through which the outer end of the handle bar is disposed with its lug engaging the inner side of the supporting plate, and a resilient support disposed on the inner side of said supporting plate in supporting cushioning relation to the outer end of the handle bar permitting swinging and limited longitudinal movement thereof.

4. The combination with a door having a chamber therein and comprising an outer panel, of a supporting plate mounted on the inner side of said panel to extend over said chamber and apertured to receive an escutcheon member, an escutcheon member secured to said plate, a bolt releasing trigger pivotally mounted on said escutcheon member, a spring acting to bias the trigger to retracted position, a handle, the inner end of the handle extending through the escutcheon plate and being pivotally connected to the trigger, the outer end of the handle terminating in a laterally disposed lug, the panel and supporting plate having openings therein through which the outer end of the handle is disposed with its lug engaging the inner side of the supporting plate, and a resilient support disposed on the inner side of said supporting plate in supporting cushioning relation to the outer end of the handle bar permitting swinging and limited longitudinal movement thereof.

5. The combination with a door having a chamber therein and comprising an outer panel, of a supporting plate mounted on the inner side of said panel to extend over said chamber and apertured to receive an escutcheon member, an escutcheon member secured to said plate, a bolt releasing trigger pivotally mounted on said escutcheon member, a spring acting to bias the trigger to retracted position, a handle, the inner end of the handle extending through the escutcheon plate and being pivotally connected to

the trigger, the outer end of the handle terminating in a laterally disposed lug, the panel and supporting plate having openings therein through which the outer end of the handle is disposed with its lug engaging the inner side of the supporting plate.

6. The combination with a support apertured to receive an escutcheon member, of an escutcheon member disposed and secured within said aperture, a bolt releasing trigger pivotally mounted on said escutcheon member, a spring acting to bias the trigger to retracted position, a handle, the inner end of the handle being pivotally connected to the trigger, the outer end of the handle terminating in a laterally disposed lug, the support having an opening therein through which the outer end of the handle is disposed with its lug engaging the inner side of the support, and a resilient supporting and cushioning element for the outer end of said handle disposed on the inner side of said plate.

7. The combination with a support apertured to receive an escutcheon member, of an escutcheon member disposed and secured within said aperture, a bolt releasing trigger pivotally mounted on said escutcheon member, a spring acting to bias the trigger to retracted position, a handle, the inner end of the handle being pivotally connected to the trigger, the outer end of the handle terminating in a laterally disposed lug, the support having an opening therein through which the outer end of the handle is disposed with its lug engaging the inner side of the support.

8. The combination with a support apertured to receive an escutcheon member, of an escutcheon member disposed and secured within said aperture, a bolt releasing trigger mounted on said escutcheon member, a spring acting to bias the trigger to retracted position, a handle, the inner end of the handle extending through the escutcheon plate and being connected to the trigger, the outer end of the handle terminating in a laterally disposed lug, the support having an opening therein through which the outer end of the handle is disposed with its lug engaging the inner side of the support, and a resilient supporting and cushioning element for the outer end of said handle disposed on the inner side of said plate.

9. The combination with a supporting member, of an escutcheon member secured to said support member, a bolt releasing trigger pivotally mounted on said escutcheon member, a spring acting to bias the trigger to retracted position,

a handle, the inner end of the handle being rigid with the handle and extending through said support and escutcheon member and being pivotally connected to the trigger, the outer end of the handle being tiltably engaged with the support, said spring also acting to yieldingly urge the handle against the escutcheon.

10. The combination with a support of an escutcheon member secured to said support and having arms extending inwardly from said support, a bolt releasing trigger pivotally mounted on said arms, a spring acting to bias the trigger to retracted position, and a handle, the inner end of the handle being rigid with the handle and extending through said support and escutcheon and being pivotally connected to the trigger in spaced relation from the pivot of the trigger, to bodily move in the arc of a circle about the pivot of the trigger, said support being provided with means tiltably and slidably supporting the outer end of the handle to permit tiltable movement of the handle and movement of the handle longitudinally of itself as the inner end of the handle is bodily moved in the arc of the circle about the pivot of the trigger, said means including a resilient supporting and cushioning element for the outer end of said handle.

11. The combination with a support of an escutcheon member secured to said support and having arms extending inwardly from said support, a bolt releasing trigger pivotally mounted on said arms, a spring acting to bias the trigger to retracted position, and a handle, the inner end of the handle being rigid with the handle and extending through said support and escutcheon and being pivotally connected to the trigger in spaced relation from the pivot of the trigger, to bodily move in the arc of a circle about the pivot of the trigger, said support being provided with means tiltably and slidably supporting the outer end of the handle to permit tiltable movement of the handle and movement of the handle longitudinally of itself as the inner end of the handle is bodily moved in the arc of the circle about the pivot of the trigger.
